UNITED STATES PATENT OFFICE.

JOSIAH C. SUTTON, OF MOUNT PLEASANT, MICHIGAN.

HEATING-STOVE.

1,314,442.

Specification of Letters Patent. Patented Aug. 26, 1919.

Application filed August 15, 1918. Serial No. 250,037.

To all whom it may concern:

Be it known that I, JOSIAH C. SUTTON, a citizen of the United States, residing at Mount Pleasant, in the county of Isabella 5 and State of Michigan, have invented certain new and useful Improvements in Heating-Stoves, of which the following is a specification.

This invention relates in general to stoves 10 having central air flues and more particularly to means for removing ashes within the ash pit from around the base of said flue.

Another object of the invention is the production of a rotary ash discharge member in 15 the form of a scraper which is revoluble around the lower end of the air flue and consists of an annular band and an annulus connected together by radial plate like arms, 20 whereby when the scraper is rotated the ashes within the ash pit will be moved to a convenient point where the same may be discharged.

With these objects in view, together with 25 others which will appear as the description proceeds, the invention resides in the novel formation, combination and arrangement of parts, all as will be described more fully hereinafter, particularly pointed out in the 30 claim, and illustrated in the accompanying drawings, in which:

Figure 1 is a perspective view of the improved heating stove.

Fig. 2 is a cross sectional view through the 35 same on the line 2—2 of Fig. 1, looking in the direction indicated by the arrows.

Fig. 3 is a cross sectional view on the same line looking downwardly.

Fig. 4 is a vertical central sectional view 40 of the stove from front to rear on the line 4—4 of Fig. 1.

Fig. 5 is a transverse sectional view through the drum of the stove on the line 5—5 of Fig. 4.

Fig. 6 is a perspective view of the rotary 45 ash discharge device, and

Fig. 7 is a top plan view of a portion of the stove showing the manner of hinging the top thereto.

In the drawings, 10 indicates the base of 50 the stove which, as shown in the drawings is cylindrical and somewhat shallow and serving also as an ash pit for the stove. The axis of the base is vertical and entirely surrounding its lower end or bottom is a foot plate 11 to which the legs 12 of the stove are

removably connected as usual. The bottom 13 may be integrally formed therewith or, as shown in the drawings, made from a separate plate suitably bolted to the base and 60 having formed therethrough at one side of the center an ash discharge opening 14, see Fig. 3, which may be of an elongated rectangular shape as in said figure or of other shape most convenient and suitable for the 65 purpose. Below the opening 14 and mounted in guides of well known form is a cut-off gate 15 which upon opening, permits the ashes to be discharged therethrough into a receptacle placed upon the floor below the 70 stove, the ash discharge device being described later.

Supported upon the base 10 and extending for a suitable distance upwardly therefrom is a fire pot 16, the walls of which converge 75 from above downwardly and are joined at the bottom to an outwardly flaring ring 17, from the outer edge of which depends a flange 18 which extends over the top of the ash pit 10 and holds the fire pot in position 80 on the base. Within the fire pot and at the bottom thereof where it joins the ring 17 is a grate 19 rotatably supported upon an inwardly projecting flange 20 integral with the fire pot, said flange being cut away at 85 the front of the stove as at 20^a to permit the passage therethrough of the grate rotating means. The grate rotating means comprises a toothed wheel 21 fixed to a shaft 22 turning in bearings 23 extending upwardly from the bottom 13 of the stove, said shaft projecting through the front of the ash pit 10 and having a polygonally formed outer end to receive a crank or other form of handle 90 by which the wheel 21 may be turned. The 95 teeth of this wheel engage teeth or notches 24 formed on or in the underside of the grate near its outer periphery and extending entirely around said grate so that when rotating the shaft 22, the grate will in turn also 100 be rotated.

Rising from the top of the fire pot 16 is the body 25 of the stove made in the form of a cylindrical drum with a door 26 at one side and an angular flange 27 secured to the 105 bottom by means of which it is supported on the fire pot. On the top of the drum 25 is an outwardly projecting flange 28 which supports the top of the stove, which is made as shown in Fig. 1 of two semi-circular 110 plates 29 and 30, each plate having a lug 31 on one end through which a pivot bolt

32 passes into the flange 28 at the top of the drum. By this means the two parts of the top plate may swing away from each other to open the top of the stove. The 5 straight edges of the plates 29 and 30 abut or lie in contact when the top of the stove is closed and so form a sufficiently tight connection between the two plates. Pivoted on the plate 29 near the lug 31 is the ornamental cap 33 of the stove which is of conical form and is provided with a number of openings 34 to permit the escape of heated air. At the rear of the stove and at the top of the drum 25 is a short pipe section 35 to which is connected in the usual manner a pipe leading to the chimney flue. The pipe section 35 as will be seen passes upwardly through an opening formed by depressions 36 in the straight sides of the 10 top plates 30 and 29, the depressions being of such shape that when the top plates are in contact the depressions will closely surround the pipe section.

Passing upwardly through the stove in 25 a vertical direction and in the central axis thereof is an air heating flue 37, said flue being open at both ends and passing at its lower end through the bottom plate 13 of the base 10. The flue 37 converges slightly 30 from its lower to its upper end, the latter end passing through an opening in the top formed by semi-circular depressions 38 in the plates 29 and 30 and terminating just above said stove top. This flue situated as 35 it is in the center of the stove will be heated on all sides by the fuel and being open at both ends, an uninterrupted circulation of air through the flue is permitted, cold air entering from the bottom and passing out 40 through the top and thence through the openings 34 in the cap 33. This heated air is distributed through the room and in connection with the air heated from the outside of the stove and radiant heat also from 45 the outside of the stove will serve to warm the room and produce a greater amount of heat in proportion to the consumption of fuel than is possible with stoves which do not have the central flue.

50 Within the ash pit 10 and surrounding the central flue 37 is an ash scraper 40 for collecting the ashes and delivering them to the opening 14 in the bottom 13 of the ash pit. This scraper comprises an exterior annular band 41 and an inner annulus 42

which fits easily over the flue 37 and is adapted to be revolved about the same. The band 41 and annulus 42 are connected by several plate like radial arms 43 which extend from the bottom to the top of said band and annulus. The scraper 40 extends upwardly from the bottom of the ash pit toward the grate 19 such a distance as will enable the ashes passing through the grate to fall within the band 41 so that when 60 revolved the arms 43 will carry the ashes from any part of the ash pit to the opening 14 and permit them to fall through the same into an ash pan placed below.

The base 10 is provided with an opening 10' therein as shown in Figs. 1 and 4. It will further be noted that the annular band 41 of the rotary scraper is provided with openings 41' therein. When the device is assembled access may be had to the rotary 75 scraper through the opening 10' in the base 10. Therefore a person may insert a poker or any suitable implement through the opening 10' to engage the rotary scraper and then by engaging the implement within 80 one of the openings 41' of the annular band 41' the push or pull upon this band will cause the scraper to be revolved, for purposes as hereinbefore set forth.

Having thus fully described my invention, what I claim as new and desire to secure by Letters Patent, is:

In combination with a heater including a vertically extending air flue and an ash pit provided with a side opening and an 90 ash discharge opening in the bottom thereof; of a rotary scraper resting upon the bottom of said ash pit and consisting of an annular band having openings therein 95 and surrounding the base of said air flue, and plate like radial arms connected to said annulus and said band, whereby an implement may be inserted through the side opening of said ash pit to engage one of the 100 openings of said annular band, thus allowing the scraper to be revolved, as and for the purposes set forth.

In testimony whereof I affix my signature in presence of two witnesses.

JOSIAH C. SUTTON.
